ABSTRACT OF THE DISCLOSURE

A process for the selective extraction of aromatic hydrocarbons from a feed stock containing both aromatic and saturated hydrocarbons. The process employs a solvent which selectively extracts aromatic hydrocarbons with respect to saturated hydrocarbons from a feed stream. The solvent is removed from a mixture of solvent and feed stock and treated to recover a concentrated stream of aromatic hydrocarbons.

BACKGROUND OF THE INVENTION

Field of the invention

This invention relates to a solvent extraction process. More specifically, the present invention relates to a process in which a sultone type compound is utilized, as a solvent, to selectively remove aromatic hydrocarbons from a feed stock containing both aromatic and saturated hydrocarbons.

Description of the prior art

The solvent extraction of aromatic hydrocarbons is well known in the art. Specifically, solvent extraction utilizing glycol and sulfolane type compounds as solvents to selectively remove aromatic hydrocarbons from mixture of saturated and aromatic hydrocarbons are well known in the art. There is a multitude of issued patents relating to processes utilizing these and derivative compounds. The art, however, has not recognized the use of sultone type compounds as solvents to selectively remove aromatic hydrocarbons from the mixture of aromatic and saturated hydrocarbons.

SUMMARY OF THE INVENTION

It is an object of this invention to provide a solvent extraction process to concentrate aromatic hydrocarbons from a feed stock containing them. It is another object of this invention to provide a solvent extraction process utilizing a sultone type compound as a selective solvent to remove aromatic hydrocarbons from a feed stock containing both aromatic and saturate hydrocarbons.

In terms of utility, the present process offers a process for the concentration of valuable aromatic type hydrocarbons which can be utilized in a multitude of operations varying from gasoline production to the production of plastics. Aromatics most readily separable utilizing the process of this invention include benzene, toluene or the xylenes. The saturated hydrocarbons in admixture with the aromatics generally comprise cyclo-paraffins or the branched or straight chain paraffins boiling substantially the same temperature range as the aromatic compounds described above.

Feeds stocks which can be used in the process of this invention include those derived from various crude fractions including straight run gasoline, reformed hydrocarbons or some of the products of catalytic cracking or hydrocracking reactions. Specific components included as feed stocks are the aromatics such as benzene, toluene, ethylbenzene, para-xylene, meta-xylene, ortho-xylene, isopropylbenzene, the diethylbenzene, the triethylbenzenes, the methylbenzenes, or some other higher boiling

aromatic compounds not specifically mentioned. The saturated hydrocarbons included in the feed stock are paraffins and cyclo-paraffins. Specifically, branched or straight chain paraffins which can be in the feed stocks are those having from 7 to and including 10 or more carbon atoms per molecule. In many instances they may have up to as many as 15 to 20 carbon atoms per molecule. Specific branched paraffins include branched or straight chain pentanes, hexanes, heptanes, octane, nonane, etc. Typical of the cycloparaffins which can be found in the feed stocks are some of the cyclopentanes, cyclohexane, and the alkyl derivatives thereof. Higher boiling cycloparaffins which also can be included in the feed stocks include the decahydronaphthalenes and bicyclo-paraffins.

Solvents which can be used in the process of this invention are chosen from the general class of compounds referred to as sultones. Sultones are described as heterocyclic compounds which contain carbon, sulfur and oxygen atoms in a configuration generally described in the structure as described below:

Wherein various substitutions which can be included at the "R" substitutional groups above include of hydrogen, methyl, or ethyl radical groups at any or all of the substitutional groups and n is an integer of one to three. Utilizing the above formula, the following material can be utilized as solvent: 1,3-propane sultone, 1,3-butane sultone, 1,4-butane sultone, 2,4-butane sultone, 1,3-pentane sultone, 2,4-pentane sultone, 3,5-pentane sultone etc. Other combinations may be included such as materials which contain methyl or ethyl groups on the end or in the middle of the chain of the above described formula. In particular, 1,3-propane sultone can be produced by the reaction of sulfur trioxide and allyl alcohol followed by dehydration.

The sultones may be utilized in relatively pure forms or in mixtures with water and/or other organic compounds including sulfolane type compounds or the ethylene glycols including di- and tri-ethylene glycol solvents. It has been found in extraction processing that small quantities of the above substances can, in many instances, enhance the separation abilities of an extract for various feed components. In particular, aromatic components in admixture with saturate components in a feed stock can be made easier to separate.

Extraction conditions include liquid phase operations with sufficient pressure to maintain such operations. Temperatures can include those from about ambient up to about 200° C. and in many instances up to about 250° C. The higher temperature limitation may, in some instance, be required to be lower than that stated where solvent easily decomposes at the temperature proposed. The percentage of water or organic materials which can be present along with the solvent during extraction operations can vary anywhere from a few percent up to as many as 10 or more weight percent.

It is contemplated that in normal operations the solvent material will contact the feed stock under extraction conditions in any one of a number of contacting devices which are known to the art. Contacting devices which can be utilized include the countercurrent flow, rotating disc contactors to allow an intimate mixing of feed and solvent materials. It is contemplated that both the extract phase and raffinate phase material can be removed from an extraction device and passed into various separation or treating means in order to eliminate solvent carry over by the raffinate stream and to allow separation of aromatics from the sultone solvent. Typically, the raf-

finate material can be passed into a water contacting device in which water can contact the raffinate material to wash any solvent carried out of the process by the raffinate stream. The extract phase material can generally be passed into an extractive distillation column in which the more volatile component of the aromatic and solvent mixture passes overhead while the higher boiling fraction is removed from the bottoms fraction. In some instances in which higher molecular weight aromatics are extracted, the solvent may instead pass overhead with the aromatics recovered in the bottom fraction. Some extract phase separation operations include an extractive distillation column in series with a fractionating column in which the extractive distillation column gives a first separation of aromatics and solvent with the fractionating column allowing a more complete separation to take place. In cases where an organic compound or water is used in admixture with a solvent, it may be required to treat the solvent with this substance in order to maintain a given concentration of this substance in the solvent before the solvent is recycled into the contacting zone. In other instances the solvent may be required to be partially regenerated or treated in order to eliminate the contaminants absorbed within it before it is returned to the contactor.

EXAMPLES

In this example a sultone material was used to illustrate a specific embodiment of the process of this invention. The apparatus used consisted of a sealed bomb which could sustain a moderate amount of pressure and temperatures up to about 200° C. The bomb was filled with a predetermined quantity of feedstock and the desired solvent and then shaken to cause intimate mixing of both the feed and solvent materials. The bomb was then placed in a constant temperature bath maintained at 121° C. with occasional agitation. After about one hour at 121° C. the contents of the bomb were sampled by drawing off substantially all of the upper raffinate and lower extract phases. The results of the experiment are shown in the table below:

EXTRACTION RESULTS USING 1,3-PROPANE SULTONE AS A SOLVENT

Material description	Wt., gms.	Wt. percent
Feedstock:		
Benzene.....	5.41	21.6
Methylcyclopentane.....	19.64	78.4
Total.....	25.05	100.0
Solvent:		
1,3 propanesultone.....	48.42	97.5
Water.....	1.22	2.5
Total.....	49.64	100.0
Raffinate phase (upper layer):		
1,3 propane sulfone.....	0.21	1.8
Benzene (Bz).....	1.75	15.2
Methylcyclopentane (MCP).....	9.57	83.0
Total.....	11.53	100.0
Weight ratio Bz/MCP.....	0.18	100.0
Extract phase (lower layer):		
1,3 propane sulfone.....	38.52	94.1
Benzene.....	1.41	3.5
Methylcyclopentane.....	1.00	2.4
Total.....	40.93	100.0
Weight ratio Bz/MCP.....	1.41	100.0
Selectivity.....	7.82	100.0

¹ Selectivity is the ratio of the ratios of Bz/MCP in the extract and raffinate phases respectively.

The water content was normalized out of the calculations for the extract and raffinate phases. The water was added to the solvent as a normal standard operating procedure since water in many cases enhances a solvent's ability to selectively concentrate two component of a feed stream in a raffinate and in an extract phase.

The selectivity of the 1,3 propane sultone for aromatic components was calculated by taking the weight ratios of benzene over methylcyclopentane in the extract and

raffinate phases respectively. As can be seen in the table above, the material tested as a solvent was able to selectively concentrate aromatic hydrocarbons in the extract or solvent phase.

5 The above example is offered as a specific embodiment of the process of this invention and is not to be taken as an undue limitation of the scope of the attached claims.

EMBODIMENT

10 A broad embodiment of this invention resides in a process for separating aromatic hydrocarbons from a feed mixture containing both aromatic and saturate hydrocarbons by contacting said feed mixtures with a solvent comprising a sultone, selectively extracting said aromatics 15 from said feed by said solvent and recovering aromatics from said solvent.

20 A more specific embodiment of this invention resides in a process for the selective extraction of an aromatic hydrocarbon from a feedstock containing aromatic and saturate hydrocarbons which process comprises contacting said feedstock with a solvent comprising a material having the formula:

wherein $n=1, 2$ or 3 , and the "R" substitutions are selected from the group consisting of hydrogen, methyl and ethyl radicals or combination thereof, at solvent extraction conditions to effect the selective retention of aromatic hydrocarbons by said solvent as compared to said saturate hydrocarbons, recovering solvent and said selectively retained aromatics and recovering said selectively retained aromatics from said solvent.

We claim as our invention:

1. A process for the selective extraction of an aromatic hydrocarbon from a feed stock containing aromatic and saturated hydrocarbons which process comprises contacting said feed stock with a solvent comprising a material having the formula:

wherein each R substitution is selected from the group consisting of hydrogen, methyl and ethyl radicals and n is an integer from 3 to 5, at solvent extraction conditions to effect the selective retention of aromatic hydrocarbons by said solvent as compared to said saturated hydrocarbons recovering solvent and said selectively retained aromatics and recovering said selectively retained aromatics from said solvent.

from said solvent.

2. Claim 1 further characterized in that said aromatic hydrocarbon is selected from the group consisting of benzene, toluene, xylene and ethylbenzene.

3. Claim 2 further characterized in that said saturated hydrocarbon is selected from the group consisting of paraffins and cycloparaffins.

4. Claim 3 further characterized in that n is 3.

5. Claim 3 further characterized in that n is 4.

6. Claim 3 further characterized in that n is 5.

7. A process for the selective extraction of an aromatic hydrocarbon from a feed stock containing aromatic and saturated hydrocarbons, which process comprises contacting said feed stock with a solvent comprising a material having the formula:

wherein each R substitution is selected from the group consisting of hydrogen, methyl and ethyl radicals, at sol-

vent extraction conditions to effect the selective retention of aromatic hydrocarbons by said solvent as compared to said saturated hydrocarbons, recovering solvent and said selectively retained aromatics and recovering said selectively retained aromatics from said solvent.

8. Claim 7 further characterized in that said aromatic hydrocarbons contain from 6 to about 15 carbon atoms per molecule.

9. Claim 7 further characterized in that said saturated hydrocarbons are paraffinic hydrocarbons having from 6 to about 20 carbon atoms per molecule.

10. Claim 7 further characterized in that said saturated hydrocarbons are cycloparaffins.

11. Claim 7 further characterized in that each R substitution is hydrogen.
